UNITED STATES PATENT OFFICE.

ALFRED CROOK, OF PHILADELPHIA, PENNSYLVANIA, ASSIGNOR TO PHILADELPHIA ROLL & MACHINE COMPANY, OF PHILADELPHIA, PENNSYLVANIA, A CORPORATION OF PENNSYLVANIA.

METHOD AND MEANS FOR CONTROLLING THE CONDENSING ACTION IN THE CASTING OF IRON ROLLS.

Application filed March 27, 1924. Serial No. 702,340.

To all whom it may concern:

Be it known that I, ALFRED CROOK, a citizen of the United States, residing at Philadelphia, in the county of Philadelphia and State of Pennsylvania, have invented certain new and useful Improvements in Methods and Means for Controlling the Condensing Action in the Casting of Iron Rolls, of which the following is a specification.

Heretofore, in the casting of rolls intended for rolling mills and the like, it has been the practice to employ iron forms or chills, commonly known as "closing-in-rings," which constitute a part of the mold and by direct contact with preselected areas of the casting, for example, the pass channels and necks, rapidly absorb sufficient heat of the casting to prevent or minimize separation of the carbon into the larger flakes making for a coarse grain. Closing-in-rings and the like chills suffer the disadvantage that they have to be constructed to conform to the desired contour of the rolls. Ordinarily, they are destroyed after an order is filled, and not infrequently because of distortion due to direct absorption of the heat of the casting, they are effective for not more than one or two casting operations, thus making it necessary to have spares on hand when a number of identical rolls is ordered at a time. Aside from the disadvantage of their short life, their proneness to distortion under expansion and contraction renders them uncertain as an element for controlling the character of the grain structure. At any rate, their effect in establishing a condensed or close-grain structure is relatively fixed and incapable of appreciable variation.

Objects of the present invention are to provide a method and means for controlling the condensing action in the casting of ferrous metal structures, particularly rolls; to provide a controlling means of the nature indicated which shall be capable of considerable variation with respect to the range and character of the condensing action; to provide for accomplishing this by indirect heat absorption, that is to say, through the intervention of controllable heat absorption media substantially insulated from physical contact with the casting; to provide a

method and means of effecting desirable alterations of the grain structure in preselected areas of the casting, which consists in utilizing the enveloping sand in the preselected areas to abstract the heat of the casting and regulating the heat abstracting capacity of the sand by means extending beyond the mold and controllable at will; to provide for variations in the range and character of the condensing action by variable adjustment of the heat absorption media which latter preferably includes a fluid circulating system; to provide for variations in the range and character of the condensing action by variable adjustment of the heat abstracting manifolds of the system as to cross-sectional area and as to their spacing from the casting and by regulating the velocity of fluid flow and the temperature of the fluid; to provide heat abstracting means which shall be substantially unaffected by the heat of the casting and therefore capable of use over and over again; and to provide heat abstracting units of the universal type, that is to say, units susceptible to ready adjustment for use with rolls widely varying in design.

In general, the method contemplates the arrangement of the fluid circulating units at varying distances from the molten metal; changes in the cross-sectional area of the units; acceleration or deceleration of fluid flow, as well as regulation of the temperature of the circulating fluid, whereby through one or more or all of such variations to control the rate of heat abstraction and thereby accurately govern the degree of hardness or the character of the grain structure in the preselected areas of the roll.

The means for carrying out the method may obviously include a variety of structures, such for example, as a system of manifolds of one or more sections of pipe embedded in the sand of the mold in spaced relation to and always out of contact with the casting, with the terminals of the manifolds extending beyond the mold to provide for forced or natural circulation of the heat discharging fluid.

One embodiment of the invention is illustrated in the accompanying drawings, wherein:

Fig. 1 is a sectional view of a sand mold

with a roll casting in elevation, the units of the fluid circuit being shown in operative position,

Fig. 2 is a section on line 2—2 of Fig. 1,

Fig. 3 is a perspective view of mated fluid circulating units.

The embodiment shown in the drawings, while preferred, is a typical illustration of any mechanical equivalent. It includes 10 fluid circulating couples consisting of mated or pairs of fluid circulating units or manifolds —1— of substantially semicircular design so that when confronted or juxtaposed they form a substantially annular 15 element. In the flexibility of their construction and arrangement they readily lend themselves to adjustment to vary the diameter of the annular element so as to accommodate different conditions or different designs of rolls. The manifolds —1— are 20 placed in the sand —2— of the mold out of contact with the casting —3—. Their terminals —4— and —5— extend beyond the mold and are connected to valved service pipes —6— and —7—, whereby to induce, naturally or under pressure, the circulation of the cooling medium which may be water, brine or other fluid. Evidently, 25 by accelerating or decelerating the rate of fluid flow, the heat loading and discharging capacities of the fluid can be modified 30 within desirable limits.

In practice the system abstracts heat from the sand in and about the preselected areas 35 of the casting and by discharging the heat of the sand insures a rapid and uniform heat abstraction from the regions of the casting in the preselected areas. The effect of this, as is well-known is to cause a close- 40 grain formation or hardening of the casting in the preselected areas.

It is to be noted that there is no metal contact with the casting, hence no chill, as such is understood. Furthermore, by disposing the coils or manifolds at different 45 distances from the casting; or by increasing or decreasing the size of the pipe; or by varying the flow of the cooling medium through the units, the degree of heat abstraction, and hence the degree of hardening 50 may be controlled with reasonable certainty.

The system described can be employed with rolls of widely varying design and since there is no direct contact with molten 55 metal it follows that the life of the manifolds is very little impaired by frequent use. The manifolds are as readily placed as the chills or closing-in-rings and are less expensive and far more effective.

Having described the nature and objects 60 of the invention, I claim:

1. Means for effecting desirable alterations of grain structure in preselected areas of roll castings, comprising, in combination, a sand mold organized to dissipate the heat 65 of the casting in the preselected areas through the medium of the sand, and means conformable to varying types of rolls for discharging the heat abstracted by the sand and including relatively adjustable fluid 70 circulating units and their service connections.

2. Means for effecting desirable alterations of grain structure in preselected areas of roll castings, comprising, in combination, a sand mold organized to dissipate the heat 75 of the casting in the preselected areas through the medium of the sand, and means conformable to varying types of rolls for discharging the heat abstracted by the sand and including cooperating mated fluid 80 circulating manifolds with service connections extending beyond the mold.

3. Means for effecting desirable alterations in grain structure in preselected areas of a roll casting, comprising, in combination, 85 a sand mold, a plurality of mated fluid circulating manifolds capable of relative adjustment to adapt them to varying types of rolls and invested by the sand so as to be out of contact with the roll, said manifolds 90 having terminals extending beyond the mold, and means for relatively controlling them.

4. A sand mold for circular objects, and independently controlled fluid circulating 95 manifolds adapted to together provide a heat-absorbing element arranged in the sand beyond the object.

5. A sand mold for circular objects, and independently controlled fluid circulating 100 manifolds adapted to together provide a heat-absorbing element encircling the object and arranged in the sand, the manifolds being relatively adjustable.

6. A sand mold for circular objects, and 105 independent fluid circulating manifolds arranged in mating pairs to encircle the object, means for circulating a cooling medium through such manifolds, the respective manifolds of a pair being independently 110 adjustable with respect to the object.

7. A sand mold for rolls, a cooling member arranged in the sand about predetermined areas of such roll, said member being made up of independently controlled fluid-circulating manifolds together conforming 115 to the external shape of the predetermined area of the roll.

In testimony whereof I affix my signature.

ALFRED CROOK.
